Theodore J. Gillies of Williamsburgh, N.Y.
Letters Patent No. 604. Dated Oct. 11th, 1853.

The Schedule referred to in these Letters Patent, and making part of the same.

To all whom these presents may come:

Be it known, that I, Theodore J. Gillies of Williamsburgh in the County of Kings, and State of New York, have invented, made, and applied to use, a new and original Design for Metallic Coffins; and I do hereby declare that the following is a full, clear, and exact description of the same, reference being had to the annexed drawing, making part of this specification, wherein Fig. 1 is a plan of the coffin with the cap or face plate removed; Fig. 2 is a side elevation; Fig. 3 is an end view of the head of the coffin; Fig. 4 is an end view of the foot; Fig. 5 is a vertical longitudinal section through the line A.A. of Fig. 1; Fig. 6 is a cross section through line B.B. Fig. 7 is a plan with the lid removed; Fig. 8 is a plan; and Fig. 9 is a section of the cap or face plate. The like marks of reference denote the same parts.

a, is the bottom of the coffin made dishing downwards, see Figs. 5 & 6, around which bottom the sides b, and ends c and d, are so formed as to give a flat bearing for the coffin to stand on. The sides and ends are of a shape similar to the usual o.g. moulding, the ends somewhat resembling the bow and stern of a ship. The cover e, is to be secured to the bottom by screws or other usual means, at the joint 11, the design of the shape being curved as shewn, consisting of an easy graceful form, being ornamental and in no way repulsive to the eye, and rather more in conformity to the model of a light and beautiful ship than the shape of any coffin heretofore in use. f, is the cap or face plate which sets into a rebate g, in the lid e, g, being a projection on one end, which is entered into a hole h, at one end of the rebate g, to retain the plate in place. i, is an opening to which an air pump may be applied, and the coffin may be provided with handles as at j.j. The size of the coffin may be varied so long as the design of the shape be preserved. — What I claim and desire to secure by Letters Patent, is the design of the shaped configuration of the coffin, as described and shewn in the drawing.

In testimony whereof, I have hereunto set my signature, this twenty first day of September in the thousand eight hundred and fifty three.

Witnesses,

Thomas G. Hawld, }
James W. Sorrell.

Theodore J. Gillies.
